(57) CLAIM

The ornamental design for a “pressure tap flange”, as shown and described.

DESCRIPTION

FIG. 1 is a perspective view of an embodiment of a pressure tap flange, according to the principles of the present invention.

FIG. 2 is a front elevation of the embodiment of FIG. 1.

FIG. 3 is a side elevation view of the embodiment of FIG. 1, the other side view being a mirror image thereof.

FIG. 4 is a plan view of the embodiment of FIG. 1.

FIG. 5 is a rear elevation view of the embodiment of FIG. 1.

FIG. 6 is a plan view of the embodiment of FIG. 1; and, FIG. 7 is a perspective view of the embodiment of FIG. 1 showing a quick release device with dust cover open, two bolts and a gasket in phantom.
